(57) **CLAIM**

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken lines immediately surrounding the photographic area represents a peripheral boundary of the design that forms no part of the claim. The eight small circular elements shown in broken lines within the photographic area, and the unshaded areas therein, represent eyelet regions which form no part of the claimed design. The broken lines showing the remainder of the shoe are for environmental purposes only and form no part of the claimed design.
